UNITED STATES PATENT OFFICE.

JAMES E. ANNEN, OF MILWAUKEE, WISCONSIN, ASSIGNOR TO THE NATIONAL PAPER CAN COMPANY, OF MILWAUKEE, WISCONSIN, A CORPORATION OF WISCONSIN.

METHOD OF MAKING PAPER CONTAINERS.

Application filed September 21, 1923. Serial No. 664,022.

I provide for rolling over an edge of the container and then forming the rolled portion into a closure seat as, for example, by pressing or mashing down the rolled portion.

5 My method is applicable to the forming of a closure seat on containers either before or after a bottom has been fixed therein. It is necessary to grip the container immediately below the portion which is to be worked on 10 in the formation of a closure seat and I provide for gripping the container through the opening which is to form the container mouth.

15 In the accompanying drawings illustrating various forms of container closures which may be made according to my method and my present preferred apparatus for carrying out the method:

20 Figure 1 is a top plan view, partly broken away, of a container having a closure formed according to my invention;

Figure 2 is a section on the line II-II of Figure 1;

25 Figures 3, 4, 5, 6 and 7 are sectional views, partly broken away, through other forms of containers made according to my invention;

30 Figure 8 is a vertical section through a forming head showing the upper portion of a container body placed therein and ready to be gripped by the head;

Figure 9 is a view similar to Figure 8, but showing the outer clamping jaws in clamping position;

35 Figure 10 is a view similar to Figure 8, but showing the supporting and operating mechanism and showing the container after it has been gripped and its upper edge rolled over;

40 Figure 11 is a view similar to Figure 8, but showing a second head with means for pressing down the previously rolled over portion of a container;

45 Figures 12 and 13 are bottom views of the inner clamping jaws showing the jaws in expanded and retracted positions;

Figure 14 is a perspective view of the clamping jaw operating cam block;

50 Figures 15 and 16 are top and side views respectively of the outer clamping jaws;

Figure 17 is a top plan view of the frame piece which supports the clamping jaws;

55 Figure 18 is a perspective view of the frame spacer.

Figures 19 and 20 are front and side elevations of one of the inner clamping jaws;

Figures 21 and 22 are side and top views of another inner clamping jaw;

Figure 23 is a sectional view, partly broken away, showing one of the detents and operating pins for the curling ring; and

Figure 24 is a sectional view showing a modified form of my apparatus.

Referring to the drawings, Figures 1 and 2 illustrate one of the simpler forms of container which may be made by my invention. The container body 1 is made of paper or the like and is bent over at the top to form the lip portion 2 of the can or container. The paper is then folded inwardly to form a flange or seat 3 for receiving a closure disc 4, which is also of paper and which is frictionally retained in place.

The can body is illustrated as being circular, but my method may be readily applied to other shapes. The raw edge 5 of the paper is folded inwardly to form a multiply closure seat 3 and to leave a smooth inner edge on the seat. The lip 2 and the seat 3 are formed by first rolling the raw edge 5 over and then pressing the rolled portion into the form shown.

If desired, the raw edge 5 may be turned upwardly into the lip 2, as shown in Figure 3, by initially rolling the raw edge further than was done with the container of Figure 2. The raw edge may also be concealed in the seat 3, as shown in Figure 4, or it may be simply turned back, as shown in Figures 2 and 5. Figure 5 shows a container having a hollow lip which is turned inwardly to provide an inturned seat for more securely retaining the closure 4. In Figure 6, the raw edge has been moved up into the lip 2 and completely turned over to form an inturned seat similar to Figure 5. Figure 7 is similar in many respects to Figure 6, but shows the raw edge 5 turned even further.

Figures 4 to 7 show a bead 6 immediately below the lip 3. This bead is incidental to manufacture and is used to insure a tight grip during the rolling and pressing operations. It may be omitted if desired, as shown in Figures 2 and 3. It is useful, however, in giving a secure grip and it also strengthens the container. In all of the con-

ainers shown in Figures 1 to 7, the raw edge of the paper is concealed. I roll the raw edge through more than 180° in order to conceal this edge. The container of Figure 2 is formed by rolling the edge through substantially 270° , and, of course, a further rolling must be resorted to if the edge is to be turned up into the lip.

The following description applies to the manufacture of the containers shown in Figures 1 to 7, all of which are circular in cross section. It will be understood, however, that the apparatus may be readily adapted to other shapes, as desired.

In the manufacture of a container according to my method, the can body 1, in cylindrical form with an upstanding raw edge 5, is inserted a predetermined distance into the operating head. As above pointed out, the style of container may be varied by varying the amount of roll; and the distance which the can body is inserted in the head, of course, is important in this respect. The head comprises three outer clamping jaws 7 having grooves 8 therein. When the outer jaws 7 are in closed position, they form a complete circle and lightly grip the can 1, as shown in Figure 9.

It will be apparent that the inner jaws 30 must have considerable movement in order to clear the seat 3 after it has been formed and I, therefore, provide six inner jaws, as best shown in Figures 12 and 13. The inner clamps comprise three jaws 9, each in the form of a segment of a circle and each having a rib 10 thereon. These jaws are spaced apart when in expanded position, and the spaces are filled by movable jaws 11, which are also provided with a bead 10. When the inner jaws are expanded, they form a complete circle with the bead 10 fitting into the groove 8. This forms the bead 6 in the can body and securely holds it in place with the raw edge and a portion of the container wall projecting above the gripped portion.

The outer clamping jaws 7 move radially in a bottom frame 12 which is secured to the machine frame 13, as best shown in Figure 10. Each of the outer jaws 7 is provided with a hardened face 14 and rollers 15. The jaws are operated by translation cams 16 formed on three arms of a cam block 17. The cam block 17 is bolted to a head 18 by pins 19 which are slidable vertically in the frame 13. The head 18 carries a pair of rollers 20 which work in a positive cam 21 driven by a power shaft 22. As the shaft 22 is rotated, the cam block 17 is moved up and down and operates the clamping jaws in or out on each movement. The initial position is, as shown in Figure 8, with the cam block 17 in top position. As it moves downwardly, the fronts of the translation cams 16 bear on the hardened faces 14 and move jaws 7 inwardly to the

position of Figure 9. Any further downward motion has no effect on the outer clamping jaws. On the up stroke, the backs of the cams 16 contact with the rollers 15 and retract the outer jaws.

The head 18 carries a pin 23 for expanding the inner clamping jaws. This pin has tapered faces 24 which bear on corresponding faces 25 on the inner jaws 11. As the pin 23 moves downwardly, the jaws 11 are expanded from the position of Figure 13 to the position of Figure 12 and they, in turn, force the clamping jaws 9 outwardly. The jaws 9 and 11 are provided at their upper ends with horizontal T-shaped portions 26 which operate in T slots 27 in a frame member 28. The frame pieces 12 and 28 are spaced apart by a guide piece 29 which holds the moving parts in their proper relative positions.

An inspection of Figure 10 will show that the gripping of the can occupies only a small part of the downward stroke. As the downward stroke continues, the head 18 comes in contact with vertically movable pins 30 and forces them downwardly. The pins 30 carry a ring 31 having a channeled lower edge 32. As the head moves downwardly, the channel 32 comes in contact with the raw edge 5 of the container and rolls it inwardly, as shown in Figure 10. The amount of rolling is, of course, dependent on the distance to which the can body was inserted in the head prior to gripping and on the lateral clearance between the inner and outer jaws.

On the up stroke of the head, the pin 23 is retracted, freeing the inner jaws, and translation cams 33 act on corresponding surfaces 34 at the outer ends of the T-shaped portions 26 of the jaws 9 and 11. The translation cams 33 are six in number and are carried on the arms of the cam body 17. The movement of the inner jaws is large as they must clear the inwardly rolled portion 2 of the cam body 1. After the inner jaws have been collapsed, the back portions of the cams 16 contact with the rollers 15 and retract the outer clamping jaws, completely releasing the can from the head.

The cam body 17 is provided with three radial slots 35 having inner flanges 36 at the bottoms thereof. As the cam body 17 is moved upwardly, the flanges 36 come in contact with the heads 37 on the pins 30 and retract the curling ring 31. At the top of the stroke, ball detents 38 in the member 28 press into grooves 39 on the pins 30 and hold the curling ring in the position of Figure 8 to permit the insertion of a new can body. The radial slots 35 are provided to allow the use of different sizes of curling rings in the production of different sizes of cans.

At the end of this operation the upper portion of the can takes the form shown in Figure 10 although the extent of rolls may be varied according to the style of can which is to be produced. The rolled container is then inserted into a second head which is identical with the apparatus just described with the exception of the curling ring 31. The curling ring 31 is replaced with a shaping ring 40 whose lower portion has a contour depending on the style of container which is to be produced. The rolled can is inserted the proper distance and the clamping jaws engage the bead 6 and enclose the rolled portion of the container. The forming ring 40 then moves downwardly and presses the rolled portion into shape, as shown in Figure 11. The jaws are then retracted and the container is removed.

It will be seen that in the above forms, the container is gripped through the opening about which the closure seat is formed and the above operations may, therefore, be carried out even though a bottom has already been inserted in the container. In Figure 24, I have shown a modified form of apparatus which is applicable for forming closure seats before a bottom has been placed in the container. In this form of apparatus, the can body 2 is slipped over an arbor 41 carried on a support 42. The can body 1 is surrounded by downwardly movable jaws 43. The head 44 moves downwardly to roll the can body or to press the rolled portion into form. Figure 24 shows the second operation. As the head 44 moves downwardly, a ring 45 engages the upper portion of the jaws 43 and presses them tightly against the can body 2. The ring 45 is carried on slidable pins 46 and is normally pressed downwardly by compression springs 47. The head 44 also carries a forming ring 48 similar to the forming ring 40.

I provide for making a container having a closure seat by rolling over an edge of the container and then forming the rolled portion into a closure seat. I further provide for gripping the container through the opening about which the closure seat is to be formed.

While I have described the preferred embodiment of my invention, it will be understood that it is not limited to the form shown, but may be accomplished by other apparatus. It will be understood further that the sequence of certain of the steps, as, for example, the forming of the bead for gripping and the gripping proper, may be interchanged and various other changes may be made within the scope of the following claims.

I claim:

1. The method of forming a closure retaining seat on a paper container, which comprises rolling the edge of the container over to form a loose roll and then pressing on the upwardly and inwardly extending portion of the roll to reverse the curvature of such portion and form it into an upstanding portion and an inwardly projecting portion adapted to receive a closure. 65

2. The method of forming a closure retaining seat on a paper container, comprising rolling the edge of the container over to form a roll substantially entirely around 75 the mouth of the container and pressing the inwardly and upwardly projecting portion of the roll in a downward and outward direction to move such portions of the roll toward the bottom and outside portions of 80 the roll and thus form an upstanding portion and an inwardly projecting flange adapted to receive a closure.

3. The method of forming a closure retaining seat at the mouth of a paper container, which comprises rolling the edge of the container over to form a roll with an open center, applying pressure to the inwardly and upwardly projecting portion of the roll to cause it to collapse and to cause 85 such portion to move downwardly and outwardly into engagement with other portions of the roll and form an upstanding flange of double thickness and an inwardly projecting flange adapted to receive a clo- 90 sure. 95

4. The method of forming a closure retaining seat on a paper container having a mouth or opening bounded by an upstanding wall, which comprises rolling the edge 100 of said upstanding wall inwardly to form a roll, the wall portion only of the container being formed into the roll and the mouth of the container being left open, and then deforming and compacting the roll to form 105 an inwardly extending closure seat.

5. The method of forming a closure retaining seat on a paper container, which comprises rolling the edge of the container inwardly to form a loose roll and then applying pressure to said loose roll in order to reverse the curvature of the inner and upper portion of the roll and thus cause such portion to move into engagement with other portions of the roll and form an up- 110 standing flange of double thickness and an inwardly projecting flange space below the edge of the container and adapted to receive a closure. 115

In testimony whereof I have hereunto set 120 my hand.

JAMES E. ANNEN.
